REMOVABLE INNER COMPARTMENT FOR A CAN

Theodore N. Nearing, Putnam Valley, N.Y., assignor to
Stauffer Chemical Company, New York, N.Y., a cor-
poration of Delaware

Filed Mar. 11, 1968, Ser. No. 10,919

Term of patent 14 years

U.S. Cl. D9—253
Int. Cl. D9—99

Fig. 1

Fig. 2

Fig. 3

Fig. 4

Fig. 5

FIG. 1 is a perspective view of a removable inner compartment for a can, showing my new design;

FIG. 2 is a top plan view;

FIG. 3 is a bottom plan view;

FIG. 4 is a side elevational view; and

FIG. 5 is an end elevational view.

I claim:

The ornamental design for a removable inner compartment for a can, as shown.
